Term of patent 14 years

(Cl. D49—1)

Fig. 1

Fig. 2

Fig. 3

Fig. 4

Fig. 1 is a perspective view of a steam cleaning machine showing my new design;

Fig. 2 is a front elevational view thereof;

Fig. 3 is a top plan view thereof; and

Fig. 4 is a rear elevational view of the same.

The side of the machine opposite that shown in Figure 1 is substantially the same in appearance differing therefrom only in having a single hook located in the center of the large tank as indicated in Figures 2 and 4.

I claim:

The ornamental design for a steam cleaning machine, as shown and described.
